CLAIM

The ornamental design for a tackle storage system, as shown and described.

DESCRIPTION

FIG. 1 is a perspective view of an embodiment of a tackle storage system, showing our new design;

FIG. 2 is a top plan view thereof;

FIG. 3 is a bottom plan view thereof;

FIG. 4 is a right-side elevational view, the left side being a mirror image thereof;

FIG. 5 is a front elevational view thereof; and,

FIG. 6 is a rear elevational view thereof.

FIG. 1.

FIG. 2.

FIG. 3.

FIG. 5.

FIG. 6.
